UNITED STATES PATENT OFFICE

2,541,377

ONE HUNDRED AND EIGHTY DEGREE
HINGEGlen W. Neely, Oak Park, Ill., assignor to The
Richardson Company, Lockland, Ohio, a cor-
poration of Ohio

Application June 16, 1945, Serial No. 599,821

8 Claims. (Cl. 16—184)

1

My invention relates to hinge structure for small containers of the type which snap by spring action into open and closed position and wherein the maximum stress on the spring control lies in between the two extremes of position of the hinge.

The particular problem for which my present invention is advanced as a solution is to provide such a snap hinge which will take open and closed positions which are 180 degrees apart, or any fractions thereof with slight modification, and which is suitable for use with plastic materials, as for example, such as are used in small boxes for jewelry and the like.

Among additional objects are the making of a hinge which is self-contained with no parts engaging the portions to be hinged together but the straps of the hinge device, which will preferably be of piano hinge type.

As an exemplary structure illustrating the novel features of my invention, I show in the drawings, and will describe a jewelry case and a hinge construction for use therewith. The novelty inherent therein will be set forth in the appended claims.

In the drawings:

Figure 1 is a perspective of a box.

Figure 2 is a plan view of the two hinge pieces.

Figure 3 is a side elevation view of the hinge.

Figure 4 is a diagram showing the hinge in full open position.

Figure 5 is a diagram showing the hinge closed.

Figure 6 is a diagram illustrating a less than 180° opening.

Figure 7 is a perspective of the hinge showing a modified form for dropping into place.

Figure 8 is a detail of a box flange to accommodate the hinge of Figure 7.

I have shown the invention as applied to a box having a container portion 1 and a lid portion 2. The wall surrounding the container portion is indicated at 1a and the wall surrounding the lid portion is illustrated at 2a. Normally the inside of the structure will be closed with a suitable fabric lining which extends loosely across the joint between the two parts and encloses and conceals all hinge construction. There is enough play in the cloth to permit of such limited projection as takes place of the hinge spring of my device when the box is closed. When the box is open there is practically no projection of the spring, as will be noted.

The two hinge portions shown have body portions 3 and 4 respectively, which have piano hinge portions 3a and 4a respectively through which a pintle pin 5 is thrust. The two ends of each hinge

2

portion are extended to form attaching leaves 6, 6, for the hinge portion 3 and 7, 7, for the hinge portion 4. Intermediate the ends, the leaf of each hinge is bent at right angles to form projecting tongues 6a and 7a.

The walls of the container portion and lid are recessed or cut away so as to permit of the attaching leaves 6, 6, to be mounted on the rising portion of the container portion wall, with a portion of the container wall lying between the attached walls recessed or cut away to provide the space 8, as can be seen in Figure 1. The space 9 in the depending wall of the lid portion is also formed by cutting away a portion of the wall between the mounting point for the two leaves 7, 7, of the hinge portion 4.

A spring is provided which has a special shape. It has a pair of hooked ends 10, 10, which hook over the free edges of the two tongue portions

20 6a and 7a. From the hook portions there are the straight portions 11, 11, which will lie parallel to the two tongue portions (see Figure 7) so that this portion of the spring can lie against the face of the two tongue portions when the hinge is open.

25 The spring is then bent into two loops 12, 12, and the outer portions of the loops are extended toward each other in a length 13. The central portion of the length 13 is bowed outwardly at 14 for the purpose of conforming to the shape of the hinge portions 3a, 4a of the two hinge halves.

If we now take the relation when the hinge is open at 180° and start to close the lid of the box, this is opposed by the two loops and the connecting portion until the lid had moved past a 90°

35 position, at which position the spring will have been extended to its utmost position. Further movement of the lid will be assisted by the spring which will tend to return to its normal shape, thus by contracting forcing the two tongue portions of the hinge to a position in the same plane, with the two attaching leaves in contact with each other.

40 This relation is shown in Figure 5. When the box is opened the spring will be caused to expand until the box lid passes the 90° position whereupon it will snap to full open position. Since each hinge leaf moves through 90° the box lid will move through 180° (Figure 4).

If it is desired to limit the opening of the box to less than 180°, but greater than 90°, the section 45 13 and the connecting bowed portion are changed as shown in Figure 6. In such a case when the lid has been forced by the spring to 135°, for example, the bowed portion 14 wil contact with the hinge pintle retaining portions of the hinge and

having bottomed will therefore hold the box lid in a partially open position under stress of the spring.

It may be noted that the sole mounting means are a pair of screws which can be inserted into a piece of plastic material without much difficulty. In all other respects the hinge structure supports the parts, and the spring does not engage any plastic wall or socket. However, if desired, the mounting of the hinge may be accomplished as shown in Figures 7 and 8.

In this instance the two hinge leaves have body portions 3 and 4, as in the first example and pintle mounting loops 3a and 4a. The intermediate leaf portions are turned at right angles to form projecting tongues 6a and 7a, as in the first instance. However, the terminal attaching portions 6 and 7 of the first example are modified. Instead of projecting from the body leaf portions 3 and 4, the mounting portions are bent as at 20 and 21, and return bent so as to be pushed into mounting slots in the box flanges and remain there by friction.

Thus as shown in Figure 8, the box wall or flange 22 is formed with the recessed portion 23, alike to the recess 8, but also two narrow recesses 24 and 25 are formed in the wall or flange. Into these recesses 24 and 25 the mounting portions 20 and 21 are inserted.

Of course a like construction will be used in mounting the other leaf of the hinge to the lid.

Figure 7 shows the hinge in open position as in Figure 4.

The device can be made in very small sizes, if desired for delicate work, and the assembly is simple, since the hinge may be mounted on the parts by screws and the hinge then pushed into place, or alternatively the spring may be frictionally set in place as last above described. The lining fabric may then be cemented down and the hinging of the box is complete.

The particular shape of the spring may be modified within the range of equivalents. In the structure described, it has the general shape of an end elevation of the hinge in its full open position. The important feature is that the major stress on the spring should be at a point intermediate the closed and open position of the hinge.

Having thus described my invention, what I claim as new and desire to secure by Letters Patent is:

1. In combination a box having flanges on its body portion and lid portion, said flanges cut away to leave matching spaces at the hinging point, and a hinge comprising two leaves hinged together, each leaf having terminal portions secured to the flanges of the body and lid adjacent the spaces, and having intermediate leaf portions extending at right angles to the body portions of said leaf, said intermediate portions located in the said spaces, and a leaf spring secured to the free edges of the said intermediate portions and surrounding the hinge intermediate said terminal portions, said spring being so shaped as to be under the major stress when the hinge is in position intermediate its open and closed relation.

2. The combination of claim 1 in which the securing of the leaf spring to the free edges

of the intermediate portions is by means of hooks on the ends of the said spring.

5 3. The combination of claim 1 in which the terminal portions of each leaf are turned parallel to the intermediate portions thereof, with the ends of said turned portions reversely bent, and in which said box flanges have slots for frictionally engaging said terminal portions at the ends of the cut-away portions of the flanges.

10 4. The combination of claim 1 in which the terminal portions extend in the plane of the body portions of the hinge leaves, and are provided with holes for reception of mounting means on the box flanges.

15 5. A snap hinge construction comprising a pair of leaves pivoted to each other at adjacent edges, said leaves movable about said pivot in a forward direction from an open position in which the leaves lie at an angle to each other to another position in which they are in substantial face-to-face relationship, said leaves having rigid extensions extending in a rearward direction, and a leaf spring engaging said extensions and passing around said pivot forwardly, said extensions positioned so that a straight line joining said extensions will lie on one side of said pivot when said leaves are open and on the other side when said leaves are in face-to-face relationship.

20 6. A 180° opening, snap hinge comprising a pair of leaves pivoted to each other at adjacent edges, said leaves movable about said pivot in a forward direction from a position in which they are coplanar to another position in which they are in face-to-face relationship, said leaves having rigid extensions which when said leaves are coplanar extend in a rearward direction, and a leaf spring engaging said extensions and passing around said pivot forwardly, said extensions positioned so that a straight line joining said extensions will lie on one side of said pivot when said leaves are coplanar and on the other side when said leaves are in face-to-face relationship.

25 7. The structure of claim 5 wherein the opening of the hinge is limited to less than 180° but greater than 90° by means of the spring, said spring being configured so that an intermediate portion thereof will contact the hinge at its pivot prior to the full opening of the hinge and hence retain it in less than fully open position.

30 8. The combination of claim 1 wherein the spring element is shaped so as to substantially conform to the contour of the hinge when the hinge is in open position.
